US0D1085680S

(12) **United States Design Patent** (10) **Patent No.:** **US D1,085,680 S**
(45) **Date of Patent:** **** Jul. 29, 2025**

(54) **SHOE**

(71) Applicant: **ROTHY'S, INC.**, San Francisco, CA (US)

(72) Inventors: **La Vion Gibson**, San Francisco, CA (US); **Caroline Swierszczyk**, San Francisco, CA (US)

(73) Assignee: **ROTHY'S, INC.**, San Francisco, CA (US)

(**) Term: **15 Years**

(21) Appl. No.: **29/917,475**

(22) Filed: **Nov. 20, 2023**

(51) LOC (15) Cl. **02-04**

(52) U.S. Cl.

USPC **D2/971**; D2/923; D2/969

(58) **Field of Classification Search**

USPC D2/919, 920, 923, 924, 929, 939, 971,

D2/969

(57) **CLAIM**

The ornamental design for a shoe as shown and described.

DESCRIPTION

FIG. 1 is a front left perspective view of a shoe showing our new design;

FIG. 2 is a rear left perspective view of the design shown in FIG. 1;

FIG. 3 is a front view of the design shown in FIG. 1;

FIG. 4 is rear view of the design shown in FIG. 1;

FIG. 5 is a right side view of the design shown in FIG. 1;

FIG. 6 is a left side view of the design shown in FIG. 1;

FIG. 7 is a top view of the design shown in FIG. 1; and,

FIG. 8 is a bottom view of the design shown in FIG. 1.

The broken lines shown in FIGS. 1-8 are included for the purpose of illustrating environmental structure of the shoe that forms no part of the claimed design.

1 Claim, 8 Drawing Sheets
